UNITED STATES PATENT OFFICE.

IDA M. ELDRIDGE, OF LOS ANGELES, CALIFORNIA, ASSIGNOR OF ONE-HALF TO LENA R. HOEFLER, OF LOS ANGELES, CALIFORNIA.

DESIGN FOR A MANICURING INSTRUMENT.

Application filed May 3, 1926. Serial No. 17,540. Term of patent 3½ years.

To all whom it may concern:

Be it known that I, IDA M. ELDRIDGE, a citizen of the United States, and a resident of the city of Los Angeles, in the county of Los Angeles and State of California, have invented a new, original, and ornamental Design for a Manicuring Instrument, of which the following is a specification, reference being had to the accompanying drawings, forming part thereof.

The figure is a perspective view of a manicuring instrument showing my new design.

I claim:

The ornamental design for a manicuring instrument, substantially as shown.

In testimony whereof I have hereunto set my hand.

IDA M. ELDRIDGE.
